(57) **CLAIM**

The ornamental design for a device for holding open a trash bag, as shown and described.

DESCRIPTION

FIG. 1 is a perspective view of the first embodiment of a device for holding open a trash bag showing our new design; FIG. 2 is a left side elevational view thereof.

FIG. 3 is a front elevational view thereof, showing the trash bag in phantom line.

FIG. 4 is a right elevational view thereof.

FIG. 5 is a rear elevational view thereof.

FIG. 6 is top plan view thereof.

FIG. 7 is a bottom view thereof.

FIG. 8 is a perspective view of the second embodiment of a device for holding open a trash bag showing our new design; FIG. 9 is a left side elevational view of the FIG. 8 embodiment.

FIG. 10 is a front elevational view of the FIG. 8 embodiment, showing the trash bag in phantom line.

FIG. 11 is a right elevational view of the FIG. 8 embodiment.

FIG. 12 is a rear elevational view of the FIG. 8 embodiment.

FIG. 13 is top plan view of the FIG. 8 embodiment; and,

FIG. 14 is a bottom view of the FIG. 8 embodiment.

The broken line showing of a trash bag in FIGS. 3 and 10 is included for the purpose of illustrating environment and forms no part of the claimed design.
